UNITED STATES PATENT OFFICE.

JOSEPH SILAS BROWN, OF HUNTINGTON, FLORIDA.

FRUIT-BOX.

SPECIFICATION forming part of Letters Patent No. 396,138, dated January 15, 1889.

Application filed April 16, 1888. Serial No. 270,846. (No model.)

To all whom it may concern:

Be it known that I, JOSEPH SILAS BROWN, a citizen of the United States, residing at Huntington, in the county of Putnam and State of Florida, have invented a new and useful Improvement in Fruit-Boxes, of which the following is a specification.

The invention relates to improvements in fruit-boxes.

10 The object of the invention is to improve the construction of fruit-boxes similar to those in common use and render them capable of having one of their sections readily and conveniently removed in order to permit an examination of their contents and then replaced without injury to the boxes; and, furthermore, the object of the invention is to provide an adjustable partition capable of being placed in position when the boxes are partly filled 15 with fruit, to reduce the pressure upon the fruit and prevent it becoming bruised during transportation.

The invention consists in the novel combination and arrangement of the parts herein- 20 after fully described, illustrated in the accompanying drawings, and pointed out in the claims hereto appended.

In the accompanying drawings, forming 25 part of this specification, and in which like letters of reference designate corresponding parts, Figure 1 is a perspective view of a fruit- 30 box constructed in accordance with this invention, showing the section capable of being slipped from under the hoops to permit access 35 to the contents of the fruit-box. Fig. 2 is a plan view of the fruit-box, the sliding section being removed to show the construction and arrangement of the adjustable partition. Fig. 40 3 is a vertical longitudinal sectional view of Fig. 1.

Referring to the accompanying drawings, A designates the body of a fruit-box of the ordinary construction, provided upon its upper face with a sliding section, B, which has 45 a kerf-slit, b. The kerf-slit b extends longitudinally about one-half the length of the sliding section B, and it forms two legs, b' and b'', which are adapted to straddle the central or middle nails, C, placed in the middle 50 and lower hoops, D D', whereby when a nail, screw, or the like, E, at the outer end of the sliding section B, to secure it in the box, is

withdrawn, the section may be slipped out from under the hoops and the contents of the box examined without removing the hoops. 55 The sliding section B is also provided with a finger-hole to facilitate the removal of it from the box A.

When it is desired to put the sliding section in place, it is slipped under the hoops, 60 and its legs b' and b'' straddle the nails C C, which enter the kerf-slit d; then a nail, E, is driven in the end of the sliding section B, which is thereby securely retained in place.

Each half of the box is divided off by adjustable partitions F, which diminish the pressure upon the fruit by taking from it one-half of its own weight and prevent it becoming bruised during transportation. These adjustable partitions are constructed 65 of suitable material and provided at their ends with grooved strips G, the grooves g being adapted for the reception of the adjacent edges of the adjustable partition. The grooved strips G, when in position at the end of the 70 adjustable partition, form flanges at the top and bottom of the adjustable partition; and to secure the adjustable partitions in place in a fruit-box nails are driven through the 75 flanges.

80 After the fruit-box has been partly packed with fruit, the adjustable partitions F are placed in the box and nailed or similarly secured in position. The packing is then completed.

85 To remove the adjustable partitions F, it is only necessary to pry off the grooved strip at one end, and then the adjustable partition may be pulled out of the groove g of the other strip G at the other end of it.

90 The ends of the fruit-box A are provided with slots or openings a a for the hands, to facilitate handling the box and to ventilate the fruit at that point. The grooved strips G cross the slots a a and form, with the enlarged portions or openings a' of said slots, 95 pockets for the hands, whereby greater ease in handling the fruit-box is secured.

100 From the foregoing description and the accompanying drawings the construction, operation, and the advantages of the invention will be readily seen; and it will be obvious that fruit-boxes constructed in accordance with this invention are provided with covers

or sections that are readily removable and replaceable without removing the hoops or injuring the fruit-box.

Having thus fully described the invention, 5 what I claim as new, and desire to secure by Letters Patent, is—

1. A crate or fruit-box comprising a body, a partition intermediate of its ends, hoops encircling the body, one of said hoops passing around the partition, and a nail or similar retaining device passing through said hoop and entering the partition, and a cover having a longitudinal kerf-slit extending from one end of the box to the partition, substantially as and for the purpose described. 15

2. A crate or fruit-box having a central

partition and end pieces, hoops passing around the crate at the central partition and end pieces, and nails passing through the central partition and one of the end pieces, in combination with a slotted cover having its legs, formed by the slot, straddling the nails, whereby the cover may be withdrawn from the crate without removing the hoops, substantially as described. 20

25

In testimony that I claim the foregoing as my own I have hereto affixed my signature in presence of two witnesses.

JOSEPH SILAS BROWN.
